UNITED STATES PATENT OFFICE.

EUGENE ATWOOD, OF STONINGTON, CONNECTICUT, ASSIGNOR TO ATWOOD MACHINE COMPANY, OF STONINGTON, CONNECTICUT, A CORPORATION OF NEW JERSEY.

SPINNING AND TWISTING SPINDLE.

Application filed March 30, 1921. Serial No. 457,105.

To all whom it may concern:

Be it known that I, EUGENE ATWOOD, a citizen of the United States, and resident of Stonington, in the county of New London and State of Connecticut, have invented a new and useful Improvement in Spinning and Twisting Spindles, of which the following is a specification.

The object of my invention is to provide 10 certain improvements in the construction, form and arrangement of the several parts of a self oiling spindle of the step and bolster type, whereby a thorough lubrication of the step and bolster bearings is obtained.

15 My invention more particularly comprises a self oiling spindle of the step and bolster type in which the base is provided with a depending step bearing portion from which 20 uprise a bolster bearing tube and an outside tube, the outside tube being spaced from the bolster tube to form an oil reservoir, and the bolster tube having one or more holes between its top and bottom to permit the circulation 25 of the oil. The outside tube is preferably extended upwardly beyond the top of the bolster tube to prevent the overflow 30 of the oil. The bolster tube is preferably provided with a series of holes at different heights between its top and bottom to ensure the proper lubrication of the spindle 35 blade in the bolster tube, one of the holes leading from the bottom of the reservoir into a chamber formed at the top of the step bearing for ensuring the proper lubrication of the step bearing.

A practical embodiment of my invention is represented in the accompanying drawings, in which,

Fig. 1 represents in vertical central section my improved self oiling spindle of the step and bolster type.

Fig. 2 represents in side elevation, the support for the spindle.

Fig. 3 represents a top plan view of the 45 same.

Fig. 4 represents a side elevation of the spindle and its whirl.

The support for the spindle is shown as comprising a base 1 provided with a depending step bearing portion 2 having a three step bore 3, 4 and 5. The smallest bore 3 forms the step bearing for the spindle blade 6. The bottom of the uprising bolster bearing tube 7 is seated in the next larger 55 bore 4 of the base. The bottom of the up-

rising outside tube 8 is seated in the largest bore 5 of the base, which outside tube is spaced from the bolster tube to form between them an oil reservoir. This outside tube extends beyond the top of the bolster tube so as to prevent the oil from flowing over the top of the outside tube as it is lifted by the spindle above the top of the bolster tube. The tapering of the spindle blade 6 at its lower end forms an oil chamber 9 in the bottom of the bolster tube above the step bearing.

The bolster tube is provided with a series of holes 10 between its top and bottom at different heights to permit the circulation 70 of the oil and the proper lubrication of the spindle blade. The lowermost of these holes 10 leads from the bottom of the reservoir into the oil chamber 9 so as to ensure the proper lubrication of the step bearing. 75

The spindle is provided with the usual sleeve whirl 11 which surrounds and is spaced from the outside tube 8 and the spindle support.

It will be seen that when the spindle is in 80 operation, the oil will be caused to flow upwardly between the spindle blade and bolster tube and through the holes 10 in the bolster tube to thoroughly lubricate the spindle blade. It will also be seen that the 85 chamber at the top of the step bearing is also kept full of oil from the reservoir so as to thoroughly lubricate the step bearing. The extension of the outside tube beyond the top of the bolster tube prevents any overflow 90 of the oil which passes over the top of the bolster tube.

It will thus be seen that a very simple arrangement is provided for the circulation of the oil without requiring a special form of 95 spindle or whirl and without changing the step and bolster bearings for the spindle.

It is evident that various changes may be resorted to in the construction, form and arrangement of the several parts without departing from the spirit and scope of my invention; hence I do not wish to limit myself to the particular construction herein shown and described, but

What I claim is:—

1. In a self oiling spindle of the step and bolster type, a spindle blade, a bolster bearing tube, an outside tube, and a spindle support comprising a base provided with a step bearing portion having a three step bore, 110

the smallest bore forming a step bearing for the spindle blade, the next larger bore forming a seat for the bolster bearing tube and the largest bore forming a seat for the outside tube, the outside tube being spaced from the bolster bearing tube to form between them an oil reservoir, the top of the outside tube extending beyond the top of the bolster tube to prevent the overflow of oil raised by the spindle blade, and the bolster tube having holes at different heights to permit circulation of the oil and lubrication of the spindle blade.

2. In a self oiling spindle of the step and bolster type, a spindle blade, a bolster bearing tube, an outside tube, and a spindle support comprising a base provided with a step bearing portion having a three step bore, the smallest bore forming a step bearing for the spindle blade, the next larger bore forming a seat for the bolster bearing tube and the

largest bore forming a seat for the outside tube, the outside tube being spaced from the bolster bearing tube to form between them an oil reservoir, the top of the outside tube 25 extending beyond the top of the bolster bearing to prevent the overflow of oil raised by the spindle blade, the lower end of the spindle blade being tapered to form an oil chamber between it and the bolster tube above the 30 step bearing and the bolster tube having holes at different heights to permit circulation of the oil and lubrication of the spindle blade, the lowermost hole opening communication between the oil reservoir and oil 35 chamber to ensure proper lubrication of the step bearing.

In testimony, that I claim the foregoing as my invention, I have signed my name this 18th day of March, 1921.

EUGENE ATWOOD.
